CLAIM

The ornamental design for a case for smartphone, as shown and described.

DESCRIPTION

FIG. 1 is a front perspective view of a case for smartphone, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of the encircled region of FIG. 1; and,

FIG. 10 is an enlarged detail view of the encircled region of FIG. 2.

The broken lines in the figures illustrate portions of the case for smartphone that form no part of the claimed design. The dash dot dash lines in FIGS. 1, 2, 9 and 10 delineate regions of the case for smartphone that are part of the claimed design and that are shown on an enlarged scale in FIGS. 9 and 10.
